UNITED STATES PATENT OFFICE.

JOHN I. ARBOGAST, OF PITTSBURG, PENNSYLVANIA, ASSIGNOR OF ONE-HALF TO LEM S. BROCK, OF BEAVER, PENNSYLVANIA, AND SEVEN AND ONE-HALF ONE-HUNDREDTHS TO FRANK C. PARK AND SEVEN AND ONE-HALF ONE-HUNDREDTHS TO HENRY L. COLLINS, OF PITTSBURG, PENNSYLVANIA.

AMALGAMATING AND ANNEALING OVEN FOR WIRE-GLASS.

No. 844,705.

Specification of Letters Patent.

Patented Feb. 19, 1907.

Application filed April 26, 1906. Serial No. 313,742.

To all whom it may concern:

Be it known that I, JOHN I. ARBOGAST, a citizen of the United States of America, residing at Pittsburg, in the county of Allegheny and State of Pennsylvania, have invented certain new and useful Improvements in Amalgamating and Annealing Ovens for Wire-Glass, of which the following is a specification, reference being had therein to the accompanying drawings.

This invention relates to annealing-ovens adapted for the manufacture of what is known commercially as "wire-glass;" and its primary object is to provide an oven in which a composite structure comprising two layers of ordinary window-glass and an interposed layer of wire netting or mesh may be amalgamated and annealed, the construction of the oven being such that the combined layers of glass and wire mesh may be first subjected to a gradually-increasing heat, then to a degree of heat sufficient to thoroughly amalgamate and anneal the layers, and finally to a gradually-decreasing heat.

A further object of the invention is to provide the oven with suitable openings on opposite sides thereof for the insertion of flattening tools or rollers for the manipulation of the upper layer of glass simultaneously with its passage through the central portion or working chamber of the oven.

The construction of the improved oven will be fully described hereinafter in connection with the accompanying drawings, which form a part of this specification, and its novel features will be set forth in the appended claims.

In the drawings, Figure 1 is a view, partly in side elevation and partly in longitudinal section, of an oven embodying the invention. Fig. 2 is a view in perspective of one of a series of pans employed in connection with the oven. Fig. 3 is a perspective view showing two sections or layers of glass with an interposed layer of wire mesh as they appear previous to treatment within the oven. Fig. 4 is a perspective view of the completed product on a smaller scale than that shown in Fig. 3. Fig. 5 is a transverse vertical section of the oven, and Fig. 6 is a transverse horizontal section on the line $x-x$ of Fig. 5.

The reference-numerals 1 and 2 designate

the opposite side walls of the furnace, and 3 the roof thereof. The space between the side walls 1 and 2 has a filling 4 of earth, the 55 upper surface 5 of which constitutes the furnace-floor.

While of course the dimensions of the oven structure may be varied, I have found that an oven approximately one hundred and ten feet in length is desirable, and the central portion of this structure, approximately twenty feet in length, I utilize as the working or heating chamber of the oven. A series of vertically-disposed flues 6 are provided on 65 opposite sides of the oven, said flues having suitable connection with gas-supply pipes 7, located on opposite sides of the oven, as clearly shown in Figs. 5 and 6. At suitable intervals between the upper ends of the flues 70 61 provide openings 8 to permit of the insertion into the working chamber of the oven of suitable flattening tools or rollers. These openings on opposite sides of the working chamber are arranged in staggered relation 75 or out of vertical alignment, and each of said openings is provided with a suitable door or closure.

To the inner surface of each of the side walls 1 and 2 is secured an angle-plate 9, extending longitudinally throughout the length of the oven and oppositely arranged, as shown in Fig. 5, to serve as a support and trackway for a series of rectangular pans 10, adapted to contain the layers of glass and 85 wire mesh. These pans are all similar in construction, and each is provided at one side with a pair of projecting perforated ears 11, and at its opposite side with a pair of projecting lugs 12, each of said lugs having an upwardly-extending pin 13, adapted to engage the perforated ears of the next adjacent pan.

Arranged above the oven and at one side thereof is a trackway 14, or what is technically known in the art as a "telegraph," from 95 which is suspended a traveling fork or grapple 15, adapted to engage the pans after the latter are emptied and return them to the front end of the oven.

Within each of the pans 10 is supported a flattening-stone 16, said stones being of a size to snugly fit within the pans, and upon each of said stones is loosely supported a rectangular frame 17, adapted to inclose the layers of

glass and wire mesh and maintain them in their proper relative positions.

Below the angle-irons 9 I provide, at suitable intervals apart, a number of roller-shafts 18, said shafts being supported in suitable bearings in the side walls of the oven and carrying a plurality of rollers 19, over which the pans travel. At the rear end of the oven I provide a device for moving the chain of connected pans through the oven, the device here shown comprising a shaft 20, having a crank-handle 21 at one end thereof, a suitable chain 22 being wound upon the shaft 20 and adapted to engage the pins 13 of the outermost 15 pan.

The present invention is distinguished from the prior art in that I employ layers, sheets, or sections of ordinary blown window-glass in connection with an interposed layer 20 of wire mesh instead of layers of molten glass having an interposed layer of wire mesh, and in carrying out the invention I provide a lower layer of ordinary blown glass of a size corresponding to the pan 10 and rectangular frame 17, then place a layer of wire mesh of corresponding size upon the glass, and then apply a second layer of glass to the upper side of the wire mesh. These several layers are fitted within the rectangular frame 25 17, which latter rests upon the flattening-stone 16, and after the desired number of pans have been thus loaded and connected by means of the perforated lugs 11 and pins 13 they are passed into the front end of the 30 oven. During the passage of the series of pans through the front portion of the oven the layers of glass are gradually heated to prepare them for the more intense heat to which they will be subjected within the central portion or working chamber of the oven, and as each pan passes through the working-chamber the heat from the several flues 6 melts the glass to the proper consistency to insure a proper amalgamation thereof with 35 the interposed layer of wire mesh. As the several pans pass through the heating or working chamber of the oven the upper layer of glass is rolled and flattened by suitable tools inserted through the openings 8, and this manipulation of the surface of the glass renders subsequent grinding and polishing unnecessary. After each pan passes 40 out of the heating-chamber it enters the rear portion of the oven and is thus subjected to a gradually-decreasing heat until it emerges 45 from the rear end of the oven in a cooled condition, so that it may be removed from the pan and the latter returned to the front of the oven to be refilled.

50 60 In the manufacture of wire-glass as hereto-

fore practiced the layers of molten glass, with the interposed layer of wire mesh, after cooling are subjected to an expensive grinding and polishing process, and the important characteristic of the present invention is that 65 this grinding and polishing are avoided, for the reason that I employ sections of ordinary blown glass which are already polished by the gathering and blowing incident to their manufacture.

Having fully described my invention, what I claim as new, and desire to secure by Letters Patent, is—

1. An amalgamating and annealing oven having a central heating and working chamber provided with oppositely-disposed vertical flues, and an extended imperforate section adjoining each end of the heating-chamber and forming extensions thereof. 70

2. An amalgamating and annealing oven 80 for wire-glass comprising parallel sides and a roof, in combination with a series of parallel shafts having bearing in the side walls of the oven and carrying rollers, the central portion of the side walls being provided with oppositely-disposed vertical flues communicating with the fuel-supply. 85

3. An amalgamating and annealing oven for wire-glass, the central portion of which is provided with oppositely-disposed vertical 90 flues in its side walls, and openings for the insertion of tools between the upper ends of the flues.

4. An amalgamating and annealing oven for wire-glass, comprising parallel side walls 95 and a roof connecting said walls, the central portion of the side walls being provided with oppositely-disposed vertical flues and openings for the insertion of flattening-tools, the openings at one side of the oven being 100 out of horizontal alignment with those at the opposite sides thereof.

5. The combination with an amalgamating and annealing oven for wire-glass, comprising a central heating-chamber, and vertically-disposed flues and tool-openings arranged at opposite sides of the oven, of trackways secured to the inner sides of the side walls, a series of detachably-connected pans adapted to travel along said guideways, 110 means for moving said pans, and a series of parallel shafts supported below the pans carrying rollers upon which the pans rest.

In testimony whereof I affix my signature in the presence of two witnesses.

JOHN I. ARBOGAST.
